MUSCLE KNEADING AND MASSAGING DEVICE

Samuel L. Conrad, Columbus, Ohio

Application July 26, 1943, Serial No. 496,133

1 Claim. (Cl. 128—57)

The invention to be hereinafter described relates to muscle kneading and massaging devices.

There are many exercising, kneading and massaging devices and machines for various uses and purposes. Some are in the nature of more or less complicated apparatus or equipment and some are for a number of purposes. Many are for muscular development or special muscular training. Some are for correction of physical defects or deformities. Others are for relief or alleviation of pains, aches, soreness and other suffering. The present invention provides a very simple, compact and inexpensive device particularly designed to treat foot and leg muscles to relieve soreness, aches and pains in those muscles and tendons and, at the same time, to provide a device for easy home use by the individual so that a user, on arriving at home, while still enduring the pain and discomfort, may have immediate relief by simply slipping off his shoes and immediately using the invention. It is so constructed and arranged that any one can apply and use it quickly and easily after the first simple explanation or demonstration.

In order to more clearly disclose the construction, operation and use of the invention, reference should be had to the accompanying drawings forming part of this application.

Throughout the several figures of the drawings, like reference characters designate the same parts in the several views.

In the drawings—

Fig. 1 is a top plan view, open and ready for use;

Fig. 2 is a side elevation, collapsed and ready for carrying;

Fig. 3 is a side elevation of Fig. 1; and,

Fig. 4 is a view similar to Fig. 2, but inverted.

One important consideration in the present invention is that it may be made entirely of wood. At the present time that is economically important because all metal used for such devices is now classed as critical material needed for war purposes. All metal parts shown in the drawings or otherwise referred to in this application may be readily substituted with wood. That, of course, includes the hinges. Wooden pins or pivots through the ends of the swinging members and into the adjacent portion of the base could readily serve the same purpose and produce a corresponding result. Since such substitutions are practically obvious and a matter of ordinary mechanical or wood working skill, it is neither necessary nor desirable to illustrate any of them. Furthermore, such unnecessary and additional

illustration and corresponding description would merely increase the record of the case with no justifying advantage. It will be understood, of course, that any other suitable material may be used.

Referring to the drawings in detail, 1 indicates a simple flat one-piece base, preferably of rectangular shape and of any suitable thickness. Although any suitable material may be used, 10 wood is preferable as readily obtainable, light weight, economical, readily workable and not classed as a critical material, at this time. For easily carrying and handling the device, a handle 2 may be provided at one end. In the position 15 shown, it provides the simplest and easiest carrying means because, from that point, the weight is best balanced or distributed, being all below the handle. It could, of course, be placed at the opposite end, or at one side or at various other 20 points. And, of course, a hand hold could be cut in or through the base at that or at any other point desired, and serve the same purpose.

Near one end of base 1 is pivoted an open frame 25 comprising two side bars 3 and connecting cross rods 4, the connecting rods being respectively near the opposite ends of bars 3. Bars 3 are shown of substantially the same length as base 1 and that is the preferred arrangement. Here, again, although any suitable material may be used, wood 30 is preferred for the reasons given. While simple standard wood hinges 5 are shown as the connections between the frame members and base, any other pivotal connections between those parts may be used. Instead of standard wood hinges, 35 for instance, wooden pivot pins or pintles could readily be substituted in well known manner. Rods 4 have been shown as simple metal rods with nuts to properly space the bars. When collapsed, the free ends of bars 3 and the adjacent end of base 1 are in the same plane and form a narrow base on which the device may be conveniently stood upright, vertically or erect, with the handle 2 at the top.

Between bars 3 and freely revoluble on rods 4 45 are rollers 6 and 7 of any suitable material, preferably, wood. Roller 6, near the fixed end of the frame is convex relatively to its length, while roller 7 is concave. Roller 7, as will be seen, is 50 at the opposite end of the frame, for purposes to be later disclosed. By providing bars 3 with several holes or bores the roller 6 may be mounted in any one of several positions relatively to roller 7 for desired adjustment. As shown in the drawings it is in the mid-way position, relatively to

the other roller or in the middle or second of the holes.

A second and somewhat shorter frame comprising bars 8 and a connecting cross rod 9 is similarly pivotally connected to the opposite end of base 1. Here, again, the hinge connection 5 may be of wood as may, also the cross rod 9. The free ends of bars 8 are angled or bevelled to selectively seat in corresponding cooperating V-notches 10 in the lower edges of the respective side bars 3. As will be clearly seen from Figs. 1 and 2, the bars 8 are beneath bars 3 or between them and base 1. They act as a prop or a support to maintain bars 3 and their rollers 6 and 7 in any one of several selected positions according to the particular adjustment desired by the particular user. Thus, in the position of Fig. 2, for instance, they support bars 3 and rollers 6 and 7 in the position shown. In that position, the device may be placed in front of a chair in which a user is seated. With the shoe removed, the user's foot, if an average adult, will be placed on the lower or convexed roller. Then the calf of the leg will fall on the concave roller near the upper end of the roller carrying frame. By seating bars 8 in different notches 10, bars 3 may be raised or lowered to give the height and inclination, or position of adjustment, desired and most acceptable to and by the particular or individual user. When so adjusted it will be positively and firmly supported in such adjusted position as long as desired against the weight and movement of the user. And by moving the axis of the convex roller toward or from the concave roller, the rollers may be selectively spaced for different leg lengths, in using the device.

In use, the calf is simply moved back and forth over roller 7, in a direction lengthwise of the bars 3. At the same time, as the foot reaches roller 6, it is rocked radially across, on and around the convex surface of that roller. It will be noticed that the surfaces of the rollers are complementary to the surfaces on which they are to be used and that is the preferred relation. As to the arch of the foot, however, a cylindrical roller or, even, roller 1 may be used, though that is not preferred. The calf of the leg is wide compared to the arch of the foot. The arch of the foot presents a relatively narrow band. So, the band of corresponding width at the low point of the concave could be used acceptably on the arch of the foot.

Using both rollers for arches, as above indicated, the device would be collapsed as in Fig. 2 and placed between two chairs of users. Each user could then apply the arch of his foot to the roller nearest him, as will be readily understood. In that way, two people could use the device simultaneously.

At this point, it may be stated that for convenience and security in handling and carrying, the device may be definitely maintained collapsed by small hooks 11 on the sides of bars 8, engaging in corresponding eyes 12 on the sides of bars 3, making a perfectly flat compact unit with no projecting parts. Various wooden securing devices may be substituted with equally satisfactory results. As will be seen, when secured in this collapsed relation, the device may be readily stood up, on end, with the handle at the top and the hook and eye fastening will maintain the flat package form, thereby making it practicable for the upright position to be held, which would not be practicable except in such package formation.

It is hardly necessary to state that the parts are

so proportioned that the rollers will be spaced a distance approximately equal to the distance between the arch and calf of the average adult. Likewise, it will be understood that the supporting and propping frame comprising the parts 8 and 9 is of such length as to give the roller carrying frame the desired inclination, when seated in one or another of the respective notches 10.

Of course, for abnormally short and abnormally long legs, the size of the device would be correspondingly shortened or lengthened, as will be well understood, and the respective proportions of the parts would be, accordingly changed as to sizes and shapes.

On reference to Figs. 2 and 4, especially 4, it will be clear that the rollers 6 and 7 project radially beyond the side bars 3. Consequently, when collapsed, as in said Figs. 2 and 4 and turned upside down as in Fig. 4, rollers 6 and 7 engage the floor or other supporting surface and act as furniture casters for the device so that it may be easily and quickly rolled where desired.

In describing the invention reference has been made to its use for relieving foot and calf soreness and troubles. While the device has been especially developed for foot and calf troubles, it is not limited to such uses. It may be applied to the arm, back, side or any other part of the anatomy desired by the user.

It is simply constructed, low in cost, easily and quickly set up for use, requires the minimum of instruction for use, is always available for use in the home when and where needed, is compact for carrying and very easily moved to any place where it may be needed.

It is thought that the construction, operation and use of the invention will be clear from the preceding detailed description.

Many changes may be made in the construction, arrangement and disposition of the several parts of the invention, within the scope of the appended claim, without departing from the field of the invention and it is meant to include all such within this application.

Having thus described my invention, what I claim and desire to protect by Letters Patent is:

A device of the character described comprising a base, a frame of slightly greater length than that of the lower leg of the average adult and swingingly mounted at one end on and in spaced relation to said base and, in collapsed position, lying parallel to and spaced from said base, a second frame independent of the first frame, swingly mounted at one end on the aforesaid base, said mounting being at the opposite end of the base relative to the mounting of the first frame on said base, said second frame, in collapsed position, lying parallel with and on said base and between said base and the first mentioned frame, said second frame supporting said first frame in operative position, two massaging rollers journaled directly in said first frame, bodily immovable relatively to said first frame, each in close proximity to the respective end of said frame and said rollers being spaced apart a distance approximately equal to the length of the lower leg of the average adult, said space between said rollers being clear for positioning and movement of the user's leg, means for selectively securing one of said rollers in adjusted positions relatively to the other of said rollers, and means carried by said second frame and engaging means carried by said first frame, securing said frames and base in parallel, compact, collapsed relation.

SAMUEL L. CONRAD.
